UNITED STATES PATENT OFFICE.

NICHOLAS POWER, OF BROOKLYN, NEW YORK.

INDICATOR FOR FILM-MAGAZINES.

1,118,512.

Specification of Letters Patent.

Patented Nov. 24, 1914.

Application filed September 18, 1913. Serial No. 790,408.

To all whom it may concern:

Be it known that I, NICHOLAS POWER, a citizen of the United States, and a resident of Brooklyn, in the county of Kings and State of New York, have invented certain new and useful Improvements in Indicators for Film-Magazines, of which the following is a specification.

This invention relates to improvements in film magazines for moving picture machines and has for its object to provide a magazine of this character in which it may be readily determined, without opening the door of the magazine, whether or not the reel is being properly driven to receive and wind the film.

In moving picture machines as at present constructed the film bearing the successively taken pictures is fed through the projecting mechanism from one reel to another, the lower reel being continuously driven to wind the film. As the film is highly inflammable it is the practice, and in many places a statutory requirement, to inclose the reels in fireproof magazines which must be kept closed during the operation of the machine. The driving mechanism for the film reel is usually tension controlled to wind the film evenly and to prevent an injurious strain being put on the fragile films, and it sometimes happens that the reel will stick or the drive will slip and not rotate the reel, in which case the film will pile up between the magazine and the projecting mechanism stopping the machine and damaging the film, whereas if the operator had been able to tell immediately when the winding stopped, the failure could be speedily corrected without danger or damage.

Another object of the invention is to provide an indicator for the purpose stated which will be thoroughly reliable in action, which will cost little to manufacture, and which can be applied to existing machines without change in their construction and without interference with their working parts.

In the accompanying drawings I have illustrated my improved indicator applied to a magazine of preferred construction and in the said drawings,

Figure 1 is a side view of the magazine equipped with the indicator; Fig. 2 is an end view thereof partly in section, and, Fig. 3 is a detail view showing the driving con-

nnection between the indicator and the reel shaft.

Referring now to the drawings, 1 indicates the magazine which is preferably formed of sheet metal and which is suspended from the base of the machine indicated at 2. The magazine is provided with a reel shaft 3 projecting through the side wall of the magazine, and to the end of the shaft is attached a slip pulley 4, whose tension is controlled by a spring indicated at 5. The film 6 passes through a slot in the top wall of the magazine and is wound on the reel 7 within the magazine. The reel is slipped over the free end of the shaft and locked in place by a tongue 8 which is pivoted in a slit in the end of the shaft and turned to a position perpendicular to the axis of the shaft to hold the reel in place as more particularly shown in Fig. 3.

The mechanism so far described is the usual winding reel construction. When the door 9 is closed none of the moving parts of the mechanism is visible to the operator, his operating crank being on the same side of the machine as the door of the magazine. My indicator is mounted on the door 9 and comprises a sleeve 10 having a flange 11 which is attached to the middle of the door with the bore of the sleeve in line with the magazine shaft. The sleeve 10 forms a bearing for a short shaft 12 to the inner end of which is attached a crank 13 whose end projects into the path of movement of the tongue 8 when the tongue is turned to its locking position. To the outer end of the shaft 12 I attach an index hand or arrow 14, which is bright or dark as the case may be to contrast with the face of the flange 11 so as to be readily discernible. The flange or dial 11 is preferably provided with an annular rim 15 projecting slightly beyond the arrow 14 so as to protect it from accident.

The operation of the device is obvious from the above description. A glance of the operator without moving from his usual position, will show whether or not the winding mechanism is functioning properly. The indicator requires no attention whatsoever. It sets itself whenever the door is closed and is out of the way when the door is open.

It does not lessen the fireproof qualities of the magazine and makes it unnecessary

to open the magazine while the machine is in operation.

Having thus described my invention, what I claim and desire to secure by Letters

5 Patent is:—

1. The combination of a fireproof magazine for moving picture machines, a door forming one side of said magazine, an indicator mounted on said door and having an 10 operating part projecting into the interior of said magazine through a closely fitted bearing, a winding reel supported in said magazine, and a driving connection between said reel and said operating part.

15 2. The combination of a magazine for moving picture films having a door adapted to close the magazine, a winding reel within the magazine, an indicator carried by the door of the magazine and having operative 20 connection with the winding reel when the door is closed.

25 3. The combination of a magazine for moving picture films having a door adapted to close the magazine, a winding reel within the magazine and an indicator carried by the door and comprising a shaft rotatably mounted in the door and having a driving

connection with the winding reel when the door is closed.

4. The combination of a magazine for 30 moving picture films, having a door adapted to close the magazine, a winding reel shaft within the magazine, a tension drive for such shaft, an indicator carried by the door of the magazine and having driving connection with said shaft when the door is 35 closed.

40 5. The combination of a magazine for moving picture films, a winding shaft therein having a locking tongue for the film reel 45 at its free end, a door adapted to close said magazine, and an indicator carried by said door and comprising a shaft in line with said winding shaft and having a driving crank adapted to project into the path of movement of said tongue when said door is closed.

Signed at New York, in the county of New York, and State of New York, this 13 day of September, 1913.

NICHOLAS POWER.
